UNITED STATES PATENT OFFICE.

JAMES H. LUTHER, OF OLEAN, NEW YORK.

GAS REGULATOR OR GOVERNOR.

SPECIFICATION forming part of Letters Patent No. 312,484, dated February 17, 1885.

Application filed December 18, 1883. (No model.)

To all whom it may concern:

Be it known that I, JAMES H. LUTHER, a citizen of the United States, residing at Olean, New York, have invented new and useful Improvements in Gas Regulators or Governors, of which the following is a specification.

My invention relates to certain improvements in gas regulators or governors and the manner of applying or setting the same.

10 My present invention is designed to render more perfect in operation the device described in and covered by Letters Patent No. 272,281, granted to me February 13, 1883; and it has for its object to provide for the passage of the gas 15 from the gas-chamber into the piston at a point about central of the latter, in order that the piston may have a substantial bearing both above and below the gas-passage in the chamber.

My invention also has for its object to provide a means for the escape of either low-pressure leakage, which may occur when the low-pressure cock is closed, and which might otherwise tend to strain the machine by admitting too much pressure under the diaphragm.

25 My invention also has for its object to provide a means to prevent the fluttering of the diaphragm and supply, which might otherwise result from a sudden admission of gas from the supply pipe or reservoir.

30 My invention also has for its object to so connect the apparatus with the high and low pressure conduits that the regulator or governor may be removed for cleaning or repairing of the same, while the flow of gas to the 35 furnace may continue under ordinary controlling-cocks; and with these ends in view my invention consists in the peculiarities of construction and arrangement hereinafter described in detail, and specifically claimed.

40 In order that those skilled in the art to which my invention appertains may know how to make and use the same, I will proceed to describe its construction and arrangement and the mode of operation, referring by letters to 45 the accompanying drawings, in which—

Figure 1 is a central vertical section of a regulator-governor embodying my improvements, the mechanism for weighting the piston being shown in elevation. Fig. 2 is a 50 modification showing the vertical pressure up-

on the diaphragm, (and consequently the piston,) accomplished by the employment of a spring the power of which is controlled or adjusted by a hand-screw. Fig. 3 is a vertical section of the upper or head portion of the piston, and showing the means employed to prevent a too sudden flow of gas to the under side of the diaphragm, and to avoid the consequent fluttering of the same; and Fig. 4 is a plan view illustrating my novel construction of the 55 governor, with the high and low pressure service-pipes.

Similar letters denote like parts in the several figures.

A represents the upper and B the lower 65 section of the governor, each formed at its point of connection with the other with cavities, as clearly shown at Fig. 1, to provide a space for the free vertical movement of the diaphragm C, which is seated between 70 the two sections and held in place by the ordinary securing-bolts. The lower section below the diaphragm-cavity is cylindrical in cross-section, and extends sufficiently far downwardly to provide for a full bearing 75 for the piston both above and below the circumferential gas-passage in the same. Surrounding the inner cylindrical wall, D, of this extension of the section B is formed an annular gas-chamber, E, which is tapped at 80 one or more points radially to receive supply-connections, as seen at F, and where more than one of such inlet-connections are provided those not in actual use are closed by screw-plugs G. The cylindrical wall D of the 85 section B is cut away circumferentially to provide a passage, a, for the gas, and the wall of the piston H, which is hollow and strengthened by vertical ribs I, is cut away about central of its length to form a corresponding passage, b, in order that the gas may flow from the gas-chamber E to the interior of the piston and escape from the bottom end thereof into the exit-passage J. The upper section, A, of the regulator or governor is provided with a 90 central hollow hub or projection, K, designed to receive and form a bearing for a vertical rod, L, designed to press with its lower end upon a screw or bolt, M, by which the diaphragm and the upper head of the piston H are se- 95 100

cured together, the upper end of said rod L passing above or through the hub K, and pivotally connected to a lever, W, the short arm of which is pivoted to a pillar or post, O, and 5 the long arm adapted to receive a sliding weight, P, the purpose of said arrangement being to load the diaphragm and piston with any predetermined degree of resistance to the gas-pressure on the under side of the diaphragm.

10 In lieu of this mechanism just described, I may employ a spring, Q, and regulating-screw R. (Shown at Fig. 2.) The upper end or head of the piston H is provided with the vertical passage, (one or more,) as described in my 15 Letters Patent herein referred to, and for the escape of the gas contained or admitted within the piston, and in order that the pressure of the same may act with greater or less power upon the under side of the diaphragm 20 and cause the same to lift and carry with it the piston, thus lessening the area of registering-space of the inlet-passages *a b*, and consequently the supply.

Having found by experience that the sudden 25 opening of the cock in the supply-pipe and the consequent sudden admission of gas under the diaphragm through the orifice, as shown in my said patent, induced to a correspondingly sudden lift of the diaphragm and 30 piston and induced to a fluttering action, I make this orifice with tapering or cone-like sides adapted to form a small ball or shot, S, and secure the same against entire removal under the force of the gas-pressure by an over- 35 lying guard plate or finger, T, and in operation I find that the gradual lift of the said ball-valve induces to a steady supply under the diaphragm, and consequent steady operation of the regulator or governor.

40 In lieu of the ball-valve shown, any other valve designed and adapted to produce the result named may of course be employed without departing from the spirit of my invention.

45 In order to provide a means for relieving the under side of the diaphragm from any excessive pressure resulting from the leakage through the piston-bearings or from any other cause, I arrange within the lower section, B, 50 of the regulator and under the diaphragm an escape-orifice connecting with an exit-tube, V, provided with a spring-valve, W, the power of which may be regulated by a hand-screw, X, in an obvious manner.

55 At Fig. 4 of the drawings I have shown my novel arrangement of governor or regulator

with reference to the high and low pressure conduits. The governor or regulator is connected by means of suitable pipes, A', with the high-pressure conduits B', and having an interposed cock, C. The exit tube or pipe of the regulator is connected by a vertical pipe, D', with the low-pressure conduit E, and provided with an interposed cock, F, the high-pressure conduit B' and low-pressure conduit 6c E' rendered such by an interposed cock, G', so that when the regulator or governor is in place and desired to be used the cock G' and F' are opened, and the gas flowing from the high-pressure conduit will follow the line indicated by the arrows, and pass through the regulator and to the low-pressure service or conduit E. Should it become necessary or desirable for any reason to temporarily remove the governor, while at the same time it might 70 be desirable to keep the fires going, the cocks C' and F' are closed, and the cock G opened to any desired degree or adjustment, when the gas from the high-pressure conduit B will pass in a direct line to the low-pressure conduit E, 75 and the governor or regulator may be disconnected.

While I have shown my improved governor or regulator in the arrangement shown at Fig. 4, it will be understood that any other governor or regulator may be arranged likewise, and operate substantially in the same manner in so far as the delivery of the gas is concerned, either in a direct line or through the governor. I do not, therefore, wish to be confined, so far 85 as this feature of my invention is concerned, to the employment of any particular kind of governor, the gist of this feature of my invention resting in the broad idea of the arrangement of the pipes and cocks with the governor, 90 whereby the latter may be cut in or out of circuit, as already described.

What I claim as new, and desire to secure by Letters Patent, is—

The hollow piston H, having the gas-passage in its head or upper end formed with a valve, S, substantially as described, to prevent sudden vibrations of the diaphragm and piston, as hereinbefore set forth.

In testimony whereof I have hereunto set 105 my hand in the presence of two subscribing witnesses.

JAMES H. LUTHER.
